CHARGE SEVERING MECHANISM

Carl W. Schreiber, Alton, Ill., assignor to Owens-
Illinois Glass Company, a corporation of Ohio

Application April 18, 1933, Serial No. 666,727

12 Claims. (Cl. 49—5)

The present invention relates to improvements in charge severing mechanism employed in connection with bottle forming machines and the like apparatus for severing gathered mold charges from the main supply body of molten glass.

An object of the present invention is the provision of a single charge severing unit common to a series of mold groups, said unit including fluid operated motors for placing it in charge severing position and actuating the cutter or shears constituting a part of said unit.

Another object is the provision in mechanism of the above character of means whereby the cutter or shears forming a part thereof will be held stationary a predetermined period of time at the charge severing position prior to actuation of the cutter or shears in the severance of gathered mold charges. Thus the cutter or shears at the time of severance of the glass will be entirely free from vibration, which if present, would result in distortion of the bottom end of the mold charge and unsatisfactory severance of the glass.

Other objects will be in part apparent and in part pointed out hereinafter.

In the drawings:

Fig. 1 is a side elevational view of the charge severing mechanism representing one embodiment of the present invention.

Fig. 2 is a fragmentary side elevational view taken from the opposite side of Fig. 1.

Fig. 3 is a sectional view taken substantially along the line III—III of Fig. 2.

Fig. 4 is a fragmentary sectional view taken substantially along the line IV—IV of Fig. 2.

Fig. 5 is a top plan view.

Fig. 6 is a fragmentary detail sectional view of the front end of the shear actuator.

Fig. 7 is a fragmentary side elevational view of the shear actuating motor and air controlling valves at the opposite ends thereof.

Fig. 8 is a vertical longitudinal sectional view of the shear actuating motor.

Fig. 9 is a sectional elevational view taken along the line IX—IX of Fig. 8.

Fig. 10 is a diagrammatic view showing the manner in which the forming machine controls operation of the charge severing mechanism, the latter being shown in top plan with parts in section.

Figs. 11, 12, 13, and 14, illustrate the successive positions of the ram and shears during a single cycle of operations. Fig. 11 shows the shears open and in their retracted position. Fig. 12 shows the shears projected and about to sever

a gathered mold charge from the supply body. Fig. 13 illustrates the manner in which a continuous movement of the shear actuating motor moves the blades together for severing a mold charge and immediately separates them. Fig. 14 is a view similar to Fig. 13 bringing out that in advance of each projection of the ram the shears are actuated in the same fashion as in the projected position.

In more or less general terms the mechanism 10 consists of a horizontal ram carriage arranged at one side of a bottle blowing machine and molten glass container substantially as shown in a copending application Serial Number 666,726, filed April 18, 1933, in the names of John E. Mc- 15 Laughlin and Carl W. Schreiber, now Patent No. 1,991,705, dated February 19, 1935. A cutter carrying ram is mounted on the carriage for reciprocation at regular time intervals in a fashion to place the cutter in charge severing and resting positions in alternation. A fluid operated motor controlled by movement of the molds of the forming machine reciprocates the ram. Another fluid operated motor which is mounted upon said ram is suitably connected to the cutter for 25 actuating it at each end of the path of reciprocation of said ram.

In the illustrated embodiment of the invention there is included a horizontal ram carriage 20 mounted upon a pedestal 21 rising from a base 30 22, said ram carriage including a pair of opposed parallel tracks 23 or ways in which a ram 24 is supported on rollers 24^a for horizontal reciprocation. A fluid operated motor 25 for reciprocating the ram is mounted upon the ram carriage 20 and extends lengthwise thereof. The piston 26 is connected to a piston rod 27 which extends through the forward end of the motor cylinder 28 and is attached to a depending lug 29 at the back end of the ram 24. Air under pressure is supplied to the opposite ends of the motor 25 (Figs. 4, 5, and 10) through pipes 30 which are connected to a reversing valve 31, the latter in turn connected to a supply tank 33 through a pipe 32. The construction of the reversing valve 45 and means for operating it may be substantially as follows: A horizontal cylinder 34 is provided at one side with a longitudinal series of three chambers 35, the central chamber being connected to the pipe 32 leading to the air supply tank 33 while the other two chambers communicate by way of the pipes 30 with the opposite ends of the ram reciprocating motor 25. Flow of air through the pipe 32 is regulated and controlled by a solenoid operated valve 32^a connected by 55

conductors 32^b to a limit switch 32^c. Cams 32^c individual to and rotating with the molds 48 of the forming machine operate through the switches to open the valve at regular time intervals. An exhaust chamber 36 provided with an exhaust port 37 is arranged diametrically opposite said series of chambers 35. All of these chambers communicate with the interior of a sleeve 38 through suitable ports 39. A differential piston 40 within said cylinder and sleeve (Figs. 4 and 10) is constructed so that in one extreme position it establishes communication between the intermediate chamber 35 and one of the adjacent end chambers and connects the opposite end chamber and the exhaust chamber 36. Movement of the piston to the opposite end of the cylinder reverses the connection between said chambers as is obvious. Air under pressure is continuously supplied to the small end of the piston through a pipe 41 which is connected at one end to the supply tank 33 and at its other end to the cylinder 34. A coil spring 41^a (Fig. 5) assists in holding the piston in its outermost position. A pipe 42 provides for supply of air under pressure from said tank to the large end of the piston 40. A solenoid operated valve 43 in the pipe 42 regulates and controls application of air to said end of the piston. A solenoid 44 associated with the valve 43 is connected through conductors 45 to a limit switch 46 which is actuated at regular time intervals by cams 47 individual to and rotating with the molds 48 of a bottle blowing machine or the like.

This reversing valve in addition to regulating and controlling the flow of air to the ram reciprocating motor similarly controls the application of air under pressure to a motor 48 which constitutes part of the shear actuating unit. For this purpose the piston 40 is connected to a rod 50 which at its outer end carries a cross head 51 or arm, designed to actuate a valve at one end of the motor 48.

Shears 52 are mounted at the forward end of the ram 24, said shears including a pair of co-operating blades 53 attached to the outer end of a pair of shear arms 54 which are pivoted to a vertical hinge pin 55. Fingers 56 and adjustable links 57 connect said shear arms with radial arms 58 carried by sleeves 59, said sleeves keyed to a pair of vertical shafts 60. These shafts have their ends journaled in suitable bearings 61 and carry a pair of pinions 62 which constantly mesh with a rack bar 63 provided at the outer end of a push rod 64. This push rod 64 is directly connected to the shear actuating unit referred to heretofore.

Operation of the shear actuating unit as indicated heretofore, is regulated and controlled by the reversing valve 31 which in turn depends upon the valve 43 and solenoid for regulation of its operation. The specific construction may be as follows: The motor 48 includes a cylinder 65 mounted upon the ram 24 and enclosing a piston 66 which is suitably connected to the adjacent end of the push rod 64. Cylinder heads 67 close the opposite ends of said cylinder 65. The head 67 at the back end of the motor 48 is provided with a rotary valve 68 which is arranged in a cylinder 69 or housing formed integral with the upper part of said head. An inlet port 70 at one end of the valve cylinder opens into a chamber 71 to which air under pressure is constantly supplied through a pipe 72 including sections pivoted together and connected to the air supply tank 33. A valve 73 regulates the flow of air

from the pipe 72 to said chamber 71. An inlet port 74 in the cylinder head 67 provides communication between the valve cylinder 68 and the motor cylinder 65. For the purpose of exhausting air from the motor cylinder, each end portion thereof is provided with a longitudinal series of small ports 75 opening into a chamber 76 communicating with the valve chamber 69 and through a port 77 with an exhaust pipe 78 opening into the atmosphere. In addition to 10 providing for exhaust of air from the motor cylinder the construction just set forth cushions stopping of the piston 66 at each end of its stroke. A valve 79 at the opposite end of the motor is identical in construction to the valve 68 with 15 the exception that it serves only to control the exhaust of air from the motor, flow of air into the corresponding end of the motor cylinder being by way of a port 80 in the lower portion of the cylinder head. 20

The valves 68 and 79 are opened in alternation in timed relation with reciprocation of the piston 66, said valves being connected together by means of a pair of arms 81 or levers and a rod 82. A spring 83 (Figs. 2 and 7) connected 25 at one end to the motor cylinder 65 and at its other end to the rod 82, normally and yieldingly holds the valves positioned as shown in Fig. 8 in which the exhaust valve 79 is closed and the other valve 68 set to permit exhaust of air from 30 the motor. A finger 84 depending from one end of the rod 82 is normally held in contact with an adjustable stop 85 carried by the motor cylinder 65. This stop adjustably limits the extent of movement of the rod under influence 35 of the coil spring and thereby regulably controls the positions of the valves 68 and 79 at the ends of the motor 48. An adjustable stop 86 at the upper end of an arm 87 rising from the ram carriage 28 is positioned to engage one of the 40 valve arms 81 during the latter portion of each retractive movement of the ram to thereby rock said arms and reverse the positions of the valves from that shown in Fig. 8 and thereby cause forward movement of the piston 66 in its cylinder 45 at the time the ram reaches its fully retracted position.

While the shears are fully projected, occupying the charge severing position, air under pressure is admitted to the front end of the motor 50 48 by way of the aforementioned inlet port 88 so that said piston is moved backward in the motor cylinder 65, such movement operating through the rod 64 and pinions 62 to bring the shear blades 53 together for the cutting operation and immediately thereafter separate them. The inlet port 88 in the cylinder head 67 communicates with a valve chamber 89 which is attached to said head and connected through a pipe 90 to the air pressure supply pipe 72. A valve 90 divides the chamber 89 into two compartments (Figs. 6 and 9) said valve being fixed to one end of a valve stem 91 which extends through a suitable guide 92 formed integral with the wall of the chamber 89. A roller 93 at the 65 outer end of the valve stem 91 is adapted for engagement with the cross head 51 which as brought out heretofore, is moved periodically in the direction of the length of said valve stem by the reversing valve unit 31. A coil spring 94 70 normally holds the valve 90 closed. A guide rod 95 is carried by a bracket 96 at the outer end of the valve stem 91, said rod sliding in a guide 97 and operating to hold the roller 93 in position for proper engagement with the cross head 51. 75

In operation, assuming that the parts are positioned as indicated in Figs. 5, 8, and 11, and that the molds of the forming machine are rotating continuously and further, that air under pressure is being applied constantly to the inner end of the reversing valve 31, the cam 32^a associated with one of the molds actuates the limit switch 32^c with the result that the solenoid operated valve 32^a is opened. Immediately, air under pressure flows to the intermediate chamber 35 of the reversing valve and thence through one of the pipes 30 to the back end of the ram reciprocating motor 25. The ram 24 is thereby projected and brings the valve stem 81 into alignment with the center of the cross head 51. At this time the other cam 47 associated with the mold 48 referred to heretofore, actuates the limit switch 46 to thereby open the solenoid valve 43. Air under pressure now flows through the pipe 42 causing inward movement of the piston 40 of the reversing valve and corresponding movement of the cross head 51 so that the valve 90 is opened to admit air under pressure to the inner or forward end of the shear actuating motor 49. Backward movement of the piston 66 substantially to the center of the motor cylinder 65 (Fig. 13) is sufficient to bring the shear blades 53 together and sever the gathered mold charge from the supply body. Additional rearward movement of said piston (shown in dotted lines in Fig. 13) operates through the rack bar 63 and pinions 62 to again separate the shear blades. Substantially upon completion of the separation of the blades air under pressure will have entered the front end of the ram reciprocating motor by way of one of the pipes 30 due to reversing of the position of the piston 40 and cause retraction of the ram. At the time the ram completes its retractive movement, the valves 68 and 79 at the opposite ends of the shear actuating motor 49 are operated by engagement of one of the arms 81 with the stop 86 and thereby so positioned that air under pressure is admitted to the back end of the motor and exhausted from the front end thereof. This results in forward movement of the piston 66 to the end of the cylinder 65 and consequent closing and opening of the shear blades as occurred in the fully projected position. The valves will be again reversed and positioned as shown in Fig. 8 at the time the ram starts its next projecting movement. In Figs. 11 to 14 inclusive, the successive positions of the piston, rack, and pinions, and the shears involved in a single cycle of operations are illustrated.

Modifications may be resorted to within the spirit and scope of the appended claims.

What I claim is:

1. In combination, a ram mounted for reciprocation between horizontally spaced cutting and rest positions, shears at one end of the ram including a pair of shear arms, a vertical hinge pin carried by the ram and supporting said arms, a pair of pinions mounted for oscillation about separate vertical axes, means providing operating connection between said pinions and shear arms whereby rotary movement of the pinions in one direction a predetermined degree moves the shears toward and away from each other, a rack bar disposed between and meshing with the pinions, and means for reciprocating the rack bar in timed relation with movement of the ram to thereby move the shear arms toward and away from each other.

2. In combination, a ram mounted for reciprocation between horizontally spaced cutting and rest positions, shears at one end of the ram including a pair of shear arms, a vertical hinge pin carried by the ram and supporting said arms, a pair of pinions mounted for oscillation about separate vertical axes, means providing such operating connection between said pinions and shear arms that rotation of the pinions a predetermined distance in one direction both closes and opens the shears, a rack bar disposed between and meshing with the pinions, a piston motor carried by the ram and including a piston and piston rod connected to the rack bar, and means operating automatically after the shears have reached the cutting position for supplying air under pressure to one end of said motor and thereby move the piston, rack bar, and pinions.

cation between horizontally spaced cutting and rest positions, shears at one end of the ram including a pair of shear arms, a vertical hinge pin carried by the ram and supporting said arms, a pair of pinions mounted for oscillation about separate vertical axes, means providing such operating connection between said pinions and shear arms that rotation of the pinions a predetermined distance in one direction both closes and opens the shears, a rack bar disposed between and meshing with the pinions, a piston motor carried by the ram and including a piston and piston rod connected to the rack bar, and means operating automatically after the shears have reached the cutting position for supplying air under pressure to one end of said motor and thereby move the piston, rack bar, and pinions.

3. In combination, a horizontal ram mounted for reciprocation between horizontally spaced cutting and rest positions, a vertical hinge pin at one end of the ram, shears including a pair of shear arms pivoted to said hinge pin, blades at the outer ends of said arms, a pair of pinions arranged side by side for oscillation about separate vertical axes, radially extending fingers connected to said pinions, links connecting the outer ends of said fingers and the shear arms, a rack bar disposed between and meshing with said pinions for closing and opening the shears on movement of the rack bar in one direction, a fluid operated motor for reciprocating said rack bar, and means for operating said motor in timed relation with movement of said ram.

4. In combination, a horizontal ram mounted for reciprocation between horizontally spaced cutting and rest positions, shears at one end of the ram, a piston motor at the other end of the ram, means providing operating connection between said piston motor and shears such that movement of the piston in one direction both closes and opens the shears, a valve at one end of the motor for regulating application of air under pressure to said end, a ram reciprocating motor operable to move the ram and thereby place said shears in cutting and rest positions in alternation, means including a reversing valve for supplying air to the opposite ends of said ram reciprocating motor in alternation, and means whereby actuation of the reversing valve when the ram is projected opens said valve in the shear actuating motor.

5. Charge severing mechanism including a horizontal ram, shears at one end thereof including a pair of shear arms, cutting blades at the outer ends of said arms, a hinge pin carried by the ram and supporting said arms, means for moving the arms toward and from each other about said hinge pin including a piston motor mounted upon the ram, means whereby actuation of the piston motor in one direction moves the arms toward each other and then separates them, automatic means for regulating and controlling the operation of said motor, and means for reciprocating the ram, the operating connection between the motor and shear arms including rack and pinion mechanism.

6. Charge severing mechanism comprising a horizontal ram, shears at one end of the ram including a pair of shear arms, cutting blades at the outer end of said arms, a hinge pin carried by the ram and supporting said shear arms, a shear actuating piston motor at the opposite end of the ram, said motor including a horizontal cylinder, a piston therein, a rotary valve at one end

of the cylinder for controlling the flow of air under pressure to and from the cylinder, a rotary exhaust control valve at the other end of said cylinder, a separate inlet valve at said other end of the cylinder, means for maintaining air under pressure to the exterior of said inlet valve and the rotary valve at the opposite end of the motor, means for actuating said valves to thereby admit air under pressure to opposite ends of the cylinder in alternation, means including rack and pinion mechanism providing operating connection between the piston and shear arms whereby movement of the piston in either direction causes the shears to move toward and away from each other, and means for reciprocating the ram to thereby place the shears in cutting and rest positions in alternation.

7. Charge severing mechanism comprising a horizontal ram, shears at one end of the ram including a pair of shear arms, cutting blades at the outer end of said arms, a hinge pin carried by the ram and supporting said shear arms, a shear actuating piston motor at the opposite end of the ram, said motor including a horizontal cylinder, a piston therein, a rotary valve at one end of the cylinder for controlling the flow of air under pressure to and from the cylinder, a rotary exhaust control valve at the other end of said cylinder, a separate inlet valve at said other end of the cylinder, means for maintaining air under pressure to the exterior of said inlet valve and the rotary valve at the opposite end of the motor, means for actuating said valves to thereby admit air under pressure to opposite ends of the cylinder in alternation, means including rack and pinion mechanism providing operating connection between the piston and shear arms whereby movement of the piston in either direction causes the shears to move toward and away from each other, means for reciprocating the ram to thereby place the shears in cutting and rest positions in alternation, and means whereby said separate inlet valve is actuated only after the shears have been placed in cutting position.

8. Charge severing mechanism comprising a horizontal ram, shears at one end of the ram including a pair of shear arms, cutting blades at the outer end of said arms, a hinge pin carried by the ram and supporting said shear arms, a shear actuating piston motor at the opposite end of the ram, said motor including a horizontal cylinder, a piston therein, a rotary valve at one end of the cylinder for controlling the flow of air under pressure to and from the cylinder, a rotary exhaust control valve at the other end of said cylinder, a separate inlet valve at said other end of the cylinder, means for maintaining air under pressure to the exterior of said inlet valve and the rotary valve at the opposite end of the motor, means for actuating said valves to thereby admit air under pressure to opposite ends of the cylinder in alternation, means providing operating connection between the piston and shear

arms whereby movement of the piston in either direction causes the shears to move toward and away from each other, means for reciprocating the ram to thereby place the shears in cutting and rest positions in alternation, and means whereby said rotary exhaust valve and the rotary valve at the other end of said motor are reversed together at the time the ram and shears reach their rest position.

9. In combination, a horizontal ram, a pair of pivoted shear blades at one end of the ram, means for oscillating the blades about their pivot including a pair of pinions arranged side by side in spaced relation, links connecting the shear blades to the pinions at a point spaced radially from their axes, and means including a rack bar meshing with the pinions for oscillating the pinions and causing the shear blades to move toward and away from each other with rotary movement of the pinions in one direction. 20

10. In combination, a pair of shear blades, arms supporting said blades and mounted for oscillation about a common vertical pivot, a pair of arms arranged side by side for oscillation about separate vertical axes, links connecting the outer ends of the last named arms and the shear blade supporting arms, and means for imparting such a degree of oscillatory movement to said last named arms that a predetermined extent of movement thereof in one direction effects movement of the shear blades toward and away from each other. 25

11. In combination, a pair of shear blades, arms supporting said blades and mounted for oscillation about a common vertical pivot, a pair of arms arranged side by side for oscillation about separate vertical axes, links connecting the outer ends of the last named arms and the shear blade supporting arms, means for adjusting the length of the links to thereby change the normal spaced relation between the cutting edges of the blades and means for imparting such a degree of oscillatory movement to said last named arms that a predetermined extent of movement thereof in one direction effects movement of the shear 45 blades toward and away from each other.

12. In combination, a pair of shear blades, arms supporting said blades and mounted for oscillation about a common vertical pivot, a pair of arms arranged side by side for oscillation about separate vertical axes, links connecting the outer ends of the last named arms and the shear blade supporting arms, means for adjusting the length of the links to thereby change the normal spaced relation between the cutting edges of the 55 blades and means including rack and pinion mechanism for imparting such a degree of oscillatory movement to said last named arms that a predetermined extent of movement thereof in one direction effects movement of the shear 60 blades toward and away from each other.

CARL W. SCHREIBER.
